Patented June 14, 1921.

FIG. 1

FIG. 2

INVENTOR
Edwin G. Rust,
BY
Nelson S. Grindall
ATTORNEY

UNITED STATES PATENT OFFICE.

EDWIN G. RUST, OF SIOUX CITY, IOWA.

CONTAINER-CLOSURE.

1,381,137.

Specification of Letters Patent. Patented June 14, 1921.

Application filed September 14, 1920. Serial No. 410,804.

To all whom it may concern:

Be it known that I, EDWIN G. RUST, a citizen of the United States, and a resident of Sioux City, in the county of Woodbury and State of Iowa, have invented certain new and useful Improvements in Container-Closures, of which the following is a specification.

My invention has for its object the production of improved and simplified means for so securing radiator and gasoline tank caps that, while they may be readily removed to open the container, they cannot be lost therefrom nor readily stolen.

The invention has, for a further object, the production of an improved container closure, simple and inexpensive in construction, yet thoroughly efficient and dependable when in use.

The above and other objects and advantages I successfully attain in the embodiments hereinafter described, defined in the appended claims and illustrated in the accompanying drawings, which form a part of this application and of which:

25. Figure 1 is a front elevation of a motor vehicle radiator neck and cap carrying a motormeter with the device of my invention applied thereto, the parts being shown in section, and Fig. 2 is a similar view of a 30 gasoline tank neck and cap, with which the device of my invention is shown, the parts being cut away.

Referring, now, more particularly to Fig. 1, 3 represents the crown of a radiator having an external threaded neck, 4, on which is usually threaded the cap, 5, carrying a motormeter, 6, rigidly secured to the cap, 5, and having an elongated cylindrical guard casing, 7, which protects the thermometer bulb and depends centrally from the cap, 5.

40. To render my device readily applicable to motor vehicles not equipped therewith, I provide a short cylindrical tube, 8, internally threaded as at 9, to be secured firmly 45 on to the neck, 4; in lieu of the cap, 5, the upper end of the tube being externally threaded, as at 10, to receive the cap, 5.

I provide a yoke, 11, adapted to embrace the opposite sides of the guard casing, 7, the 50 upper ends of the arms of the yoke being widened and curved, as at 12, to encompass the casing and provided with ears, 13, adapted to receive bolts, 14, whereby the yoke may be firmly clamped to the casing. The web 55 of the yoke carries a rigid, depending bolt, 15, which passes freely through a slot, 16,

in a flat arm, 17, formed at one end with an eye, 18, pivoted on a horizontal pin, 19, secured in the wall of the tube, 8. The head, 20, on the lower end of the bolt, 15, prevents displacement of the bolt from the arm, 17. This construction, it will be observed, permits free rotation of the cap and the arm, 17, and is of such a length and so formed as to permit the cap to be removed from the neck or tube, laterally, as will be clearly understood from Fig. 2.

In the construction shown in Fig. 2, 21 represents the portion of a gasoline tank provided with a neck, 22, threaded to receive the cap, 23. On to the neck, 22, I thread a tube, 24, similar to the tube, 8, and the upper end of which is adapted to receive the cap, 23. From the center of the cap rigidly depends a bolt, 25, which passes freely through the link, 17, constructed and pivoted to the tube as described with reference to Fig. 1. Obviously, the tubes, 8 and 24, may be integral parts of the containers.

Having thus described my invention, what I claim as new and desire to secure by Letters Patent of the United States is:

1. A closure for a container having a tubular neck comprising a cap adapted to be rotated to secure and remove it to and from the neck, a central bolt depending from the cap, a slotted arm pivoted to the neck to oscillate vertically and through which the bolt passes, and a stop on the bolt below the arm.

2. An attachment for a container having a neck and a closure adapted to be secured to and removed from the neck by rotation, and having a central depending part, comprising a member adapted to be secured to said part and having a depending bolt, a slotted arm pivoted to the neck to oscillate vertically and through which the bolt passes, and a stop on the bolt below the arm.

3. An attachment for a container having a threaded neck, and a closure adapted to be screwed on to the neck and having a central depending part, comprising a tube adapted to be screwed onto the neck, and threaded to receive the closure, a clamp to be secured to said part and having a central depending bolt, a slotted arm pivoted to the tube to oscillate vertically, and through which the bolt passes, and a stop on the bolt below the arm.

In testimony whereof, I have hereunto set my hand this 10th day of September, 1920.

EDWIN G. RUST.
